UNITED STATES PATENT OFFICE.

MONROE GUETT, OF HARTFORD, CONNECTICUT, ASSIGNOR TO THE HART & HEGEMAN MANUFACTURING COMPANY, OF HARTFORD, CONNECTICUT, A CORPORATION OF CONNECTICUT.

FLUSH WALL SWITCH.

Application filed April 18, 1924. Serial No. 707,361.

This invention relates to flush wall-switches for electrical circuits, and is of special utility when embodied in so-called toggle or tumbler wall-switches for control 5 of indoor lighting circuits.

It is desirable that all such switches, in a given installation, shall be set to operate in the same sense, so that when any of the operating handles is turned downward the 10 circuit controlled by it will be interrupted, and its lamp or lamps extinguished, and when any of the handles is turned upward, the circuit will be completed to light the lamps, or vice versa, and it is also desirable 15 that the face-plates of such switches bear an indication above and below the handle, of the circuit condition, that is, a marking consisting of the words "Off" and "On" or the equivalent.

20 It is a common occurrence, however, for the workmen to set some of the switches in reverse position, a condition that is not properly disclosed by the face-plate and, until the electric current from the street 25 main is turned on, such errors can only be detected by removal of the face-plates and an examination of the operating parts of the switches, which is difficult to accomplish and involves an expensive duplication of labor, 30 as well as delay.

The object of the present invention is to provide a flush wall-switch having a face-plate with suitable visual indications of circuit conditions, and so constructed that it 35 can only be attached in one sense upon the switch, with the result that if the switch itself has been set in the wrong sense, a reliable indication of that fact will be displayed to the workman before he completes 40 the installation.

In the drawings, Fig. 1 is a front elevation of an electrical wall-switch in the construction of which this invention has been embodied; and Fig. 2 is a longitudinal section 45 of the same in place, with parts shown in elevation, and parts broken away to reveal inner structure; Fig. 3 is a side elevation, on a smaller scale, of a modification; and Fig. 4 is a front elevation thereof.

50 In the embodiment of this invention selected for illustration, the part designated by the reference character 1 is an electrical outlet-box or flush receptacle, set in the wall 2 of a building, containing a switch-block 55 or porcelain receptacle 3 enclosing the

switch mechanism. The latter may be of any desired type and that shown in Fig. 2 comprises contact terminals 4 and 5 and binding screws 6 and 7, to which the circuit wires (not shown) are connected in the 60 usual way.

The switch blade 8, mounted to rock on axis 9, is actuated by a tumbler or toggle handle 10 which works in conjunction with a spring 22 to snap the blade from the position shown, in which the current is off, to a position in which the blade contacts with, and connects, the terminals 4 and 5, and turns the current on.

Such action is conventional, and need not 70 be described further, except to say that the handle 10 is moved upward, in the instance illustrated, to close the circuit, and down to open it, and preferably all the similar wall-switches in the installation are set to operate in the same sense, and the face-plates of such switches are desirably marked with "On" and "Off" legends, so that the condition of the circuit can be seen, even if there 75 is no current.

In accordance with this invention, means are provided to prevent improper assemblage of the switch structure and its face-plate so that the indication afforded by the latter will always accurately agree with the 80 condition of the switch, thus giving a reliable indication on each switch of the condition of its circuit for each position of the handle 10, and any suitable means may be provided to accomplish this object.

As one convenient structure, a face-plate 11 is provided, having a central aperture 12 to accommodate the handle 10, this face-plate being furnished with such indicia as the words "On" and "Off", in proximity to 95 the handle 10, to indicate the condition of the circuit when the handle points toward "On" or "Off", as the case may be.

This face-plate is fastened to the switch-structure by suitable means, herein shown as 100 screws 13 and 14 passing through holes 15 and 16 in the face-plate and screwed into threaded holes 17 and 18 in the metal mount or frame 19 by which the receptacle is mounted on the outlet box 1. In this position the central aperture 12 of the face-plate fits over the boss or collar 21 at the base of the handle.

The mount or frame 19 is shown as secured 105 in place upon the box 1 as usual by screws 110

20, and supports the porcelain receptacle 3, and in general may be of conventional structure, as may also be the face-plate 11, but in accordance with this invention, the holes 15
 5 and 16 in the face-plate are placed at different distances from the center of the face-plate aperture 12, so that the distance marked "A" on Fig. 1 is greater than the distance "B" and the holes 17 and 18 in the member
 10 19 are at correspondingly different distances from the pivoted axis of the handle, and the face-plate 11 can only be connected to the mount 19 by the fastening-screws 13 and 14 when the holes 15 and 16 register with the
 15 holes 17 and 18, which only occurs when the plate 11 is assembled with the mount 19 as illustrated, and not in reverse relation.

Accordingly, when the handle 10 points toward the word "Off" it furnishes a reliable
 20 indication that the switch blade 8 occupies the illustrated position, with the circuit broken, and when the handle 10 points toward the word "On" the indication thus furnished that the circuit is completed can be
 25 relied on as accurate.

Any attempt by the workmen to attach the face-plate with the "Off" mark on the lower side of the plate, when the switch has not been set so that the handle points down when
 30 the current is off, will be frustrated because the screw holes will not register and the plate cannot therefore be fixed to the mount. The workman will be obliged, in such case, to mount the plate in an inverted condition, in
 35 which case the plate indications will accurately agree with the switch condition. But if it is desired that all of the switches in a given installation shall be set so that each handle points down when off, then the fact
 40 that this particular switch is not so set becomes at once apparent to the workmen, or if not to him, to the inspector, and even before the circuit has been connected to the supply mains. The inverted condition can
 45 of course be detected at a glance and without looking into the outlet box, which has heretofore been necessary and at the cost of considerable time on the part of the inspector, unless the current has been temporarily
 50 turned onto the building. Obviously the location of the screw holes in the relation stated involves no special structure of face-plate and the latter can be stamped up from sheet metal with bent margins that simulate
 55 the bevelled edges of a heavier type of plate, without increased expense of manufacture and for this reason the use of the described screw holes constitutes the preferred form of the invention.
 60 It is so preferred also for the reason that such fastening screws constitute positioning means directly intermediate the face-plate and the switch frame and as the switch frame is the most accurately adjusted member of the wall-switch, such a directly inter-

mediate form of means to prevent improper assemblage of the switch structure and its face-plate is most desirable.

My improvement is also applicable to forms of flush wall-switch other than the tumbler type, and Figs. 3 and 4 illustrate a modification in which my invention is applied to a wall switch of the push-button type, comprising a flush receptacle 1, containing a switch 3, both similar to those above described, and a face-plate 23 secured to the switch by fastening screws 13 and 14 which pass through holes 15 and 16 in the face-plate and are screwed into threaded holes formed at 17 and 18 in a switch member 19 like that shown in detail in Fig. 2.

The switch is operated in the usual manner by a pair of push-buttons 24 and 25 which pass through holes 26 and 27 respectively formed in the face-plate 23 at equal distances "C" and "D" from the center of the switch, but the holes 15 and 16 for the fastening screws 13 and 14 are placed at different distances from the center, so that the distance marked "A" on Fig. 4 is greater than the distance "B".

The face-plate 23 can thus be connected to the receptacle 1 and its switch 3 only when the holes 15 and 16 in the face-plate register respectively with the corresponding screw holes 17 and 18, these holes 17 and 18 being formed at similarly unequal distances from the switch center, as hereinbefore described in a more detailed manner with respect to the holes bearing the same reference characters in the structure shown in Figs. 1 and 2.

The push-button 24 operates the switch to turn the current on, in the instance illustrated, and the push-button 25 operates to turn it off, and this arrangement is indicated preferably by the words "On" and "Off" with which the face-plate is provided, these words being preferably situated as shown, with the word "On" between the screw 13 and the button 24, while the word "Off" is placed below the button 25, to offset the asymmetrical position of the screws 13 and 14.

It is desirable that all the wall-switches in the installation be set in the same sense, for the reasons already detailed, and if any wall-switch constructed as shown in Figs. 3 and 4 be set in the reverse sense, the words "On" and "Off" will indicate the misplacement, as they will be upside down.

This indication is reliable, for if the switch has been set in the wrong sense, the face-plate cannot be connected therewith to show the words "On" and "Off" as illustrated in Fig. 4, for the reason that if the screw-hole 15 in the face-plate registers with the hole 18 in the switch, and the screw-hole 16 registers with the hole 17, then the push-buttons 24 and 25 will not properly enter their proper holes 26 and 27 respectively,

and conversely, if the workman fits the plate to the push-buttons, and then attempts to fit the screws 13 and 14 through the holes 15 and 16 into the holes 17 and 18, he can-
5 not do so, as the holes 15 and 16 will not register with the holes 17 and 18.

Accordingly, he will be thus notified that he has set the switch 3 in the wrong sense, and if he leaves the face-plate off, or at-
10 taches it upside down, the improper setting of the switch will be evident to an inspector, even before the current is turned on.

Having illustrated and described my in-
vention thus fully, and suitable means by
15 which the same may be carried into effect, I wish it to be understood that the invention is not limited to the specific materials and structure selected for illustration and de-
scription.

20 What I claim as new and desire to secure by Letters Patent is:

1. A switch assembly comprising a switch mechanism, a face-plate, switch operating means, projecting therethrough by way of
25 an aperture or apertures symmetrically ar-

ranged with reference to the plate, and mov-
able to tangibly different positions of rest to operate the switch, and means unsym-
metrically located with reference to said operating means for securing the face-plate 30 to the switch mechanism.

2. The combination with an outlet box, of a wall-switch having an actuating tumbler-
handle, a face-plate having an aperture sur-
rounding said tumbler-handle and within 35 which it can be rocked, and a pair of screws transfixing said face-plate and screwed into said switch, at unequal distances from said aperture, to fasten said face-plate to said switch invariably in the same relation, said 40 face-plate displaying the word "On" in position to correspond to said tumbler handle when rocked to close the circuit, and displaying the word "Off" in position to be 45 similarly indicated by said tumbler handle when rocked to open the circuit.

In testimony whereof, I have signed this specification.

MONROE GUETT.
